UNITED STATES PATENT OFFICE

EDGAR R. DURGIN, OF NEWARK, NEW JERSEY, ASSIGNOR TO NEW JERSEY OPTICAL COMPANY, OF NEWARK, NEW JERSEY, A CORPORATION OF NEW JERSEY

DESIGN FOR A BRIDGE FOR SPECTACLES OR SIMILAR ARTICLES

Application filed April 23, 1931. Serial No. 39,603. Term of patent 7 years.

To all whom it may concern:

Be it known that I, EDGAR R. DURGIN, a citizen of the United States, residing in Newark, county of Essex, State of New Jersey, have invented a new, original, and ornamental Design for a Bridge for Spectacles or Similar Articles, of which the following is a specification, reference being had to the accompanying drawings, forming part hereof.

Fig. 1 is a view in front elevation of a bridge for spectacles or similar articles showing my new design; and

Fig. 2 is a view in top plan of the same.

I claim:

The ornamental design for a bridge for spectacles or similar articles, substantially as shown.

In testimony whereof I have hereunto signed my name this 21st day of April, A. D. 1931.

EDGAR R. DURGIN.
